SHEET FEEDER

Don E. Loeber, Closter, N. J., assignor to Remington Rand Inc., New York, N. Y., a corporation of Delaware

Application September 5, 1947, Serial No. 772,297

3 Claims. (Cl. 271—36)

1

The present invention relates to improvements in sheet feeders, particularly those adapted for feeding relatively small sheets and cards.

The invention provides a sheet feeder adapted to rapidly feed the discrete sheets one at a time in successive order from a stack of sheets arranged in superimposed edgewise relation on a suitable support.

The invention provides a feeder having a rotatable feed roll adapted to engage an end sheet of a series of superimposed sheets mounted in edgewise relation on supporting and stripper plates wherein the stripper plate cooperates with the feed roll to prevent the feeding of more than one sheet at a time through its spaced position with respect to the periphery of the feed roll and its resiliency. This feeder provides a simple yet efficient and relatively inexpensive construction that can be operated to successively feed discrete sheets rapidly from a stack of sheets supported by the feeder. A suitable sheet guide member is provided for cooperation with the feed roll and stripper plate for engaging the opposite edges of end sheets engaged on the stripper plate for cooperation with the stripper plate in holding the end sheet in position to have the surface along one margin engage the feed roll and for cooperation with the stripper plate in holding and guiding sheets next to the end sheet so as to secure the feeding of only one sheet at a time in rapid succession.

The invention provides a sheet feeder that is adapted to take various sizes of sheets and cards, such as used for indexing and recording data, and feed them in successive order rapidly. The feeder is of a relatively simple construction inexpensive to manufacture and easy to attach to other types of machines that are adapted to receive the successively fed sheets for subsequent operation thereon, such as a document photographing machine for photographing copies of records on the sheets, and a feeder that is inexpensive to operate, has relatively few moving parts requiring less maintenance and relatively few adjustments to secure efficient operation.

In the drawings:

Fig. 1 is a side elevation with portions broken away and shown in cross section illustrating details of construction of a feeder built according to the invention and applied to a document photographing machine conventionally illustrated in dot and dash lines.

Fig. 2 is a vertical cross section through the feeder showing a series of sheets in position and diagrammatically illustrating how the feeder works.

2

Fig. 3 is an enlarged detail cross section taken on line 3—3 of Fig. 1 illustrating the bearing mounting for the feed roller shaft.

Fig. 4 is a plan view of the feeder with portions broken away to illustrate details of construction.

Fig. 5 is an elevation of the feeder from the sheet delivery end with portions of the feed and stripper plates at the opposite end broken away.

Fig. 6 is an enlarged detail cross section showing the adjustable connection between the stripper plate and the feed plate.

A supporting plate 1 is provided with ends 2 adapted to receive suitable securing means for attaching the feeder to a document photographing or other type of machine or support on which it is to be used. Feed plate 3 is engaged over the upper end of supporting plate 1 and arranged in inclined relation, as shown in Figs. 1 and 2, with the upper end of plate 1 engaging the central underside of feed plate 3. Feed plate 3 has depending side walls 4 along opposite side edges secured to the side edges of supporting plate 1 in a suitable manner. Side walls 4 provide means for rigidly attaching and supporting feed plate 1 in the inclined position and at the forward or feed end of the feeder they are formed with bearing projections 5 extending in advance of the lower leading edge of feed plate 3. Bearing projections 5 have bearing collars 6, Fig. 3, one on each projection, for receiving a ball bearing 7 in each collar which receives and rotatably mounts opposite ends of feed shaft 8 in advance of and in substantially radial relation to feed plate 3 in a manner illustrated in Figs. 1 and 2. Pulley 9 is rigidly secured to the right hand end of feed shaft 8 as shown in Fig. 4 to receive endless belt 10 engaged over pulley 11 of smaller diameter rigidly connected with larger diameter pulley 12 rotatably mounted on stub shaft 13 carried by adjustable bracket 14.

Adjustable bracket 14 is mounted on the right hand side wall 4 by means of a suitable set screw 15, Fig. 1, having portions cooperating with a slot in bracket 14 for adjustably mounting stub shaft 13 in position to secure the desired tension on the belts for driving feed shaft 8. An electric motor 16 mounted on supporting plate 1 provides a source of power for driving feed roll shaft 8 and feeding the sheets in successive order. Motor 16 has a drive pulley 17 on the end of the drive shaft thereof provided with an endless belt 18 engaged over pulleys 12 and 11. The provision of the two belts and pulleys 11 and 12 mounted on bracket 14 provide a convenient speed reduction drive between motor 16 and feed shaft 8 so that shaft 8 is operated at the desired speed while bracket 14

may be adjusted to secure the desired tension on the belts.

A feed roll 19 of rubber or other suitable material having a friction surface is mounted in the central portion of shaft 8 in the manner shown in Figs. 4 and 5. Feed roll 19 is cylindrical in shape and has its periphery spaced from the lower leading edge of feed plate 3 as shown in Figs. 2 and 4. A stripper plate 20 is mounted on the upper inclined face of feed plate 3 for limited adjustment by means of set screws 21. Set screws 21 are threadedly mounted in feed plate 3 while stripper plate 20 has a pair of apertures through which set screws 21 extend that are larger than the shanks of the set screws passing therethrough, as shown in Fig. 6. This provides for a limited adjustment of stripper plate 20 so that the lower leading edge may be adjusted into a spaced parallel position to the periphery of feed roll 19 to leave the desired space required for the passage of a sheet that is engaged and fed by feed roll 19 while the end of the stripper plate prevents two sheets from being fed simultaneously.

A pair of sheet guide strips 22 have spring clips 23 on one end frictionally engaged over the upper edge of feed plate 3 in the manner shown in Figs. 1 and 4 for securing guide strips 22 for adjustment toward and from each other between the sides of feed plate 3 for guiding sheets supported on the feed and stripper plates to slide down inclined feed and stripper plates 3 and 20 respectively, toward the periphery of feed roll 19. Strips 22 are normally positioned in adjacent but spaced relation to the sheets to be fed. The lower end of stripper plate 20 extends beyond the lower leading edge of feed plate 3 in the manner shown in Fig. 2, for example, so that by using resilient material for stripper plate 20, the free end will flex relative to feed plate 3 and cooperate with feed roll 19 in the feeding of sheets one at a time in successive order.

In feeding sheets and cards with the present feeder, they are arranged in edgewise relation for support on feed and stripper plates 3 and 20 respectively, in the manner shown in Fig. 2 in which the lower edges of the sheets indicated at 24 will slide downwardly along stripper plate 20 toward feed roll 19 by reason of the action of gravity and the inclination of feed and stripper plates 3 and 20. A follower 25 may provide suitable weight to slide downwardly on feed and stripper plates 3 and 20 respectively for urging the sheets downwardly toward the periphery of feed roll 19. The cards or sheets are supported in an inclined relation with respect to the feed and stripper plates in which they are arranged at a relatively small acute angle to a plane perpendicular to the feed and stripper plates in the manner shown in Fig. 2. This secures a slight offsetting of the upper and lower edges of the sheets relative to each other in the manner illustrated in Fig. 2 which facilitates the guiding and feeding of the sheets.

A sheet guide is generally indicated by numeral 26 for holding and guiding the sheets in the inclined position above described. This sheet guide comprises bracket 27 mounted on the machine carrying the feeder in fixed relation with respect to supporting plate 1, feed roll 19 and stripper plate 20. A rail 28 is rigidly secured to bracket 27 and has shoe 29 slidably mounted thereon. Shoe 29 has central strip portion 30 slidably engaging the face of rail 28. Return bent ends 31, on opposite sides of strip portion 30, embrace

opposite edges of rail 28 for slidably and frictionally retaining shoe 29 in an adjusted position thereon.

A lateral projection 32 having a curved free end 33 provides the sheet engaging portion on the shoe for engaging the end sheet and those adjacent thereto at the edges opposite those engaged with stripper plate 20 for supporting and holding the sheets to be fed in the desired inclined offset position on the feed and stripper plates, as shown in Fig. 2. In addition, this shoe has curved end 33 arranged to cooperate with the resilient end of stripper plate 20 in such a way that it aids in separating an end sheet from the adjacent sheet as it engages feed roll 19 so as to prevent the feeding of more than one sheet at a time. Shoe 29 may be adjusted into any desired position on rail 28, as suggested by the dot and dash line illustration in Fig. 2, showing other positions of adjustment for the shoe on the rail from the full line position. This adjustment of shoe 29 provides for holding and feeding sheets of various sizes and the adjustment of the shoe on rail 28 into the desired position for each size of sheet to be fed secures an efficient feeding operation in cooperation with feed roll 19 and stripper plate 20.

A curved delivery plate 34 has one margin secured to the lower under side of feed plate 3 as shown in Fig. 2. The central portion of delivery plate 34 is curved into concentric spaced relation about feed roll 19 while the opposite free margin guides a fed sheet outwardly away from the feeder into the machine on which the feeder is mounted in the desired direction.

In operation feed roll 19 is rotated at a constant speed through the operation of motor 16. Cards or sheets to be fed are placed in position on the upper surface of the feed and stripper plates, as shown in Fig. 2, with shoe 29 adjusted to engage the upper edges of the sheets, as illustrated. The sheets tend to slide down stripper plate 20 so that the lower marginal portion of the end sheet of a group mounted on edge on stripper plate 20 will move into engagement with the periphery of feed roll 19. The friction surface will immediately tend to feed the end sheet downwardly as shown in Fig. 2 past the end of stripper plate 20 in view of the clockwise rotation of feed roll 19 as shown in Fig. 2 in the normal operation of the feeder.

Stripper plate 20 is adjusted to have its edge adjacent to the periphery of feed roll 19 spaced from feed roll 19 a distance approximately equal to the thickness of the sheet or card to be fed and not as great as the thickness of two such cards or sheets. With the coaction of guide shoe 29 and the resiliency of the free end of stripper plate 20 feed roll 19 will move the lower margin of a sheet by frictional engagement therewith past the free end of stripper plate 20 to engage curved delivery plate 34 for delivery of the end sheet outwardly from the feeder. The free resilient end of stripper plate 20 will cooperate in the feeding operation with the periphery of feed roll 19 to strip the sheet next to the end sheet from the end sheet being fed and prevent two sheets from being fed simultaneously in overlapping relation. The resiliency and slight flexibility of stripper plate 20 in cooperation with the construction of guide shoe 29 and the inclined position of the sheets tends to secure a separation of an end sheet from the adjacent sheet so that it can be readily and rapidly fed by feed roll 19 down and about curved delivery plate 34 in a manner that will be clear from

Fig. 2. This feeder is adapted to feed index cards, record sheets and tabulating machine cards into a photographic recording machine in successive order at a speed approximating 500 or more per minute.

It will be obvious that the feeder is of simple construction with few moving parts thereby providing a feeder that is economical to manufacture. Guide strips 22 are adjustable to positions preferably in spaced relation to the ends of the cards or sheets supported on the feed and stripper plates but in case such cards being fed should happen to slide out of alignment they will be guided by guide strips 22 toward the feed roll. It is obvious that suitable means may be provided for directly securing bracket 27 of the sheet guide to sides 4 of the feeder, if desired, so as to directly attach the sheet guide to the remainder of the feeder construction to form a single unit.

The invention claimed is:

1. A sheet feeder comprising a feed plate inclined downwardly toward the leading edge, a feed roll mounted for rotation with its axis in spaced relation to the leading edge of and in substantially the same plane as said feed plate with the periphery parallel to and adjacent said leading edge, a stripper plate on said feed plate having a resilient end projecting beyond the leading edge of said feed plate in substantially radial relation to said feed roll, means for adjustably securing said stripper plate on said feed plate with said resilient end spaced from the periphery of said feed roll an amount substantially equal to the thickness of a sheet to be fed and less than the thickness of two such sheets, and a guide having an inclined sheet engaging face mounted in spaced relation to and above said feed roll and stripper plate in a position to engage the edges of sheets nearest said feed roll and opposite to the edges of said sheets engaging said stripper plate to support said sheets on edge on and in cooperation with said feed and stripper plates slightly inclined to a plane perpendicular to said feed plate over said feed roll to present the margin of an end sheet engaged with the end of said stripper plate to the periphery of said feed roll, and said sheets being normally urged toward said feed roll by said guide and said resilient end of the stripper plate flexing with the feeding of the end sheet from its inclined position, whereby the adjacent end sheets in their slightly inclined position are unequally moved to separate the sheets, the one from the others, preparatory to feeding thereof in succession.

2. A sheet feeder comprising a feed plate inclined downwardly toward the discharge end and having laterally depending sides formed at the lower end of said feed plate into bearing projections extending beyond the lower end of said plate, an upright supporting plate engaged under said feed plate between said depending sides, and secured thereto in the central portion, a feed shaft extending in spaced parallel and substantially radial relation to the lower end of said feed plate and having the ends rotatably mounted on said bearing projections, a cylindrical feed roll

mounted on said feed shaft with the periphery spaced from the lower edge of said feed plate, a stripper plate adjustably mounted on said feed plate in substantially radial relation to said feed roll for movement of an edge into close spaced parallel proximity to the periphery of said feed roll with a margin at said edge extending beyond the lower edge of said feed plate, said margin of said stripper plate being resilient for lateral flexing in cooperation with said feed roll during sheet feeding operation for retaining sheets to be fed from said feed and stripper plates in edgewise relation thereon while said feed roll engages and feeds an end sheet past said stripper plate, the flexing of said stripper plate by the feeding end sheet effecting a pre-fed separation of the adjacent succeeding sheets, a curved delivery plate on the lower end of said feed plate extending in spaced concentric relation about the periphery of said feed roller for directing sheets fed by said feed roll outwardly from the lower end of said feeder, a motor mounted on said supporting plate, drive connections between said motor and feed shaft for rotating said feed roll in operation of said motor, and a guide for engaging the edges of sheets opposite those engaged on said stripper plate and cooperating with said stripper plate to hold and guide sheets on said stripper plate into position to have an end sheet engaged and fed by said feed roll.

3. A sheet feeder comprising a feed plate inclined downwardly toward the discharged end, a stripper plate adjustably mounted thereon and having a flexible margin projecting beyond the lower end of said feed plate for supporting sheets to be fed for sliding movement on edge toward the lower end thereof, a feed roll rotatably mounted in radial relation to said stripper plate with the periphery spaced from the resilient end of said stripper plate a distance equal substantially to the thickness of a sheet to be fed, and a guide having a rail extending in outwardly extending relation to said feed roll and a shoe adjustable on said guide formed with an angularly extending end for engaging the edges of end sheets opposite the edges engaging said stripper plate and cooperating to press the end sheets extending over said feed roll against the fielding action of the flexible margin of said stripper plate, into position for the extreme end sheet to be engaged and fed by said feed roll off the end of said stripper plate, while the adjacent end sheets are retained by said stripper plate.

DON E. LOEBER.
